4 Claims. (Cl. 200—148)

This invention relates to a pressurized gas circuit breaker, with multiple interruption, in which several impulse-operated interrupting contacts and at least one set of isolating contacts, the latter being open in the switched-out position of the circuit breaker, are connected in series, the interrupting contacts being arranged in pairs within the twin interrupter chambers, at least one pair of said chambers being mounted on an insulator column, while the isolating contacts, situated in the isolator chambers, are supported by a separate insulator column.

The continually increasing demands on the switching capacity of circuit breakers have led to the use of interrupting contacts, which perform the actual interruption, in conjunction with isolating contacts, which maintain the interruption in the switched-out position. The interrupting and isolating contacts are connected in series. At the same time both types of contacts must operate in such a manner that the isolating contacts are opened after the interrupting contacts, as soon as the flow of current in the latter has ceased. The isolating contacts when opened provide sufficient insulation to allow the interrupting contacts to be closed again. For a predetermined operating voltage a definite number of isolating contacts are required, depending on their formation, while the number of necessary interrupting contacts can vary as a function of the current to be interrupted. In order to achieve, within a definite rated voltage, a suitable construction of a series of circuit breakers, graded according to the current to be interrupted, it has been proposed that the interrupting contacts be arranged in pairs in twin interrupter chambers and that these chambers be mounted on an insulator column. The isolating contacts are similarly situated within the isolator chambers which are mounted on a separate insulator column. Thus, the extinguishing medium is led to both sets of contacts at the same time. It has been shown, however, that such a breaker had a relatively long extinguishing period whereby as a result of the ever increasing growth of short-circuit currents in large high voltage networks it was no longer possible to hold the effect of the short circuits on the various equipment in the circuit sufficiently small.

In order on the one hand to shorten the time of interruption of the breaker and on the other hand to arrive at a simple constructional form, it is proposed in this invention that the insulator column which carries the isolating contacts should consist of an operating valve situated at its base, a supporting insulator which contains a channel through which the pressurized gas flows to operate the contacts and the approximately horizontal isolator chambers arranged at the top of the supporting insulator. The isolator chambers are constantly under gas pressure and communicate with an elongated compressed gas tank, on which all three insulator columns upstand, through at least one of the insulator columns supporting the interrupting contacts, said insulator columns having a pneumatic operating mechanism situated at their base connected through an insulating rod to the operating valves situated in the interrupter chambers.

Examples of apparatus for carrying out the ideas be-

2

hind this invention are shown in the accompanying drawings:

FIG. 1 shows an example of the construction of one pole of a circuit breaker within all three insulator columns.

FIG. 2 illustrates a further example of the construction of one pole of a circuit breaker also with three insulator columns.

FIG. 3 shows on a larger scale closer details of the control equipment of a circuit breaker according to the invention.

With reference now to FIG. 1, which illustrates one pole of a multi-pole circuit breaker, numeral 1 indicates an elongated tank containing a pressurized gas on the middle of which the insulator column 2 upstands. This column comprises an operating valve 2a affixed to the base, the two-part hollow supporting insulator 2b and the two isolator chambers 2c in which the isolating contacts are contained. The supporting insulator 2b contains the channel 2d for the gas which actuates the isolating contacts in the isolator chamber 2c by means of the operating valve 2a. Upstanding upon each end of the gas tank 1 is an insulator column 3 which has a pneumatic operating mechanism 3a at its base and which also supports, on a multiple-part supporting insulator, the twin interrupter chambers 3c, in which the interrupting contacts (not shown in the figure) are arranged in pairs. The supporting insulators 3b are also hollow and contain the insulated rod 3d, which connects, in the usual way, the pneumatic operating mechanism 3a with the operating valves (not shown) which are mounted in the twin interrupter chambers 3c. The curved pipe 3e connects the interior of the supporting insulator 3b pneumatically with the gas tank 1. The gas line 4 connects the isolator chambers 2c to the gas tank 1 through the center of the supporting insulator 3b. A non-return valve can be built into the gas line 4 which prevents a flow-back of the pressurized gas from 2c to 3b. The interrupting contacts, situated in the twin interrupter chambers 3c, and the isolating contacts, in the isolator chambers 2c, are connected in series between the external electrical terminals 5 and 6. The primary circuit of the current transformer 7 is connected between the lower twin interrupter chamber of the insulator column 3 on the left and the left-hand-side isolator chamber of the insulator column 2. The transformer 7 is thus situated in the immediate vicinity of the left-hand-side insulator column 3 thus attaining the optimum space-saving arrangement. Item 8 is the control block which is connected on one side through the pneumatic line 9 with the operating valve 2a of the insulator column 2 and on the other side through the electrical conductor 10 with the operating mechanism 3a of the insulator column 3. The arrangement as shown in FIG. 1 is particularly suitable when the terminals 5, 6 of the breaker are required on the top of the breaker pole.

The arrangement as shown in FIG. 2 is somewhat different and is especially advantageous when, because of the layout of the conductors in the installation, it is desired that the terminals 5, 6 of the breaker be placed at a relatively lower level, i.e., at somewhat the same level as the lower twin interrupter chambers 3c. In this case an isolator 11 can be situated in the immediate vicinity of the current transformer 7, thus saving space, and both the terminals 5 and 12 lie at approximately the same level. The isolator chambers 2c are then situated at the same level as the twin interrupter chambers 3c which is easily achieved by using an intermediate piece 2e in the insulator column 2. The remaining parts in FIG. 2 are designated with the same reference numbers as the corresponding parts in FIG. 1.

FIG. 3 shows in enlarged dimensions the closer details of the control of the insulator columns. On the left-hand side of the gas tank 1 a portion of the insulator column 3, which carries the interrupter chambers 3c (FIG. 1) is shown. At the foot of this insulator column the pneumatic operating mechanism 3a is situated and this consists of a piston 3f placed in the housing 3g. The piston 3f is connected to the operating valves (not shown in the figure) in the twin interrupter chambers by the insulated rod 3d, which itself is situated in the center of the supporting insulator 3b. This supporting insulator 3b is permanently connected to the gas tank 1 through the bent tube 3e. 3h is a preliminary valve which is connected to the armature 3k of the magnet 3l by the valve rod 3i. The magnet 3l is a permanent magnet and also is provided with a winding 3m. The left end of the valve rod 3i is connected to the resetting piston 3n against which the spring 3o acts, the spring being placed in the space to the left of the piston 3n. This space is connected to the space under the piston 3f by the hole 3p. The hole 3p can also be constructed as an adjustable orifice in the usual way. The gas line 3q is also connected to this space while the gas line 3r is connected to the space at the right of the resetting piston 3n. The operating space of the preliminary valve 3h is permanently connected to the gas container 1 by the tube 3s. A similar insulator column 3 is symmetrically placed at the right-hand side of the gas tank 1. For the sake of clarity this insulator column has been omitted in the figure. The insulator column 2, which carries the isolator chambers 2c (FIG. 1), contains at its foot an operating valve 2a which is connected to the gas tank 1 by the supports 2f whereby the exit side opens through the tube 2g into the channel 2d of the insulator column 2b. The valve plate 2h is connected to the piston 2k by the valve rod 2i, said piston 2k being contained in the housing 2l to which the line 9 is connected, which in turn leads to the pneumatic exit side of the control block 8. The control block 8 consists of the switch-out valve 8a with its associated spring operator 8b and its trip releaser 8c as well as the switch-in valve 8d with its associated spring operator 8e and its trip releaser 8f. The valves 8a, 8d are constructed in the usual way as servo valves, the inlet side of the valve 8a being connected to the gas tank 1 by the tube 8g while the outlet side of the valve 8d is connected to the operating valve 2a by the gas line 9. The outlet side of the valve 8d is also connected to the gas line 3r through the intermediate switch of the impulse valve 8h which consists of a through-bored valve body 8i and a reloading spring 8k whereby the latter is mounted between 8i and the housing. The space above the driving piston of the switch-out valve 8a is connected to the gas line 3q through the non-return valve 8l. Each of the spring operator release mechanisms 8b, 8e has a cam 8m, 8n, which is mounted on the shaft 8o, the shaft itself being connected through the linkage 8p to the pneumatically operated spring loaded mechanism 8q. The incoming electrical conductor 10a is joined to both the winding 3m of the tripping magnet 3l by the conductor 10 and the tripping magnet 8c by the conductor 10b.

The operating principle of the arrangement described is as follows:

To trip the breaker an electrical impulse is applied through the conductors 10a, 10, 10b to the tripping magnets 3l and 8c. In this way the field of the tripping magnet 3l is weakened to such an extent that the pressure acting on the valve plate of the preliminary valve 3h opens this valve against the force of the spring 3o and thus releases the armature 3k of the magnet. The pressurized gas flows under the piston 3f forcing it together with the rod 3d upwards thereby causing, in the usual manner, the operating valves 3t, situated in the twin interrupter chambers 3c (FIG. 3), to open the in-

terrupting contacts. The tripping magnet 8c which also serves to switch off the operating current, is simultaneously activated. Thus, the spring operator release mechanism, which is constructed as a knuckle-joint, unlatches 5 and the switch-out valve 8a opens. The pressurized gas flows from the gas tank 1 through the pipe 8g, the valve 8a and the valves 8d, which as a result of its differential-piston method of construction opens permitting the gas to flow through the gas line 9, and against the driving piston 2k of the operating valve 2a. This valve opens permitting the pressurized gas from the tank 1 to flow through the tube 2g into the channel 2d of the supporting insulator 2b, thus opening, in the usual manner, the isolating contacts situated in the isolator chambers 2c (FIG. 1). The necessary delay between the opening of the isolating contacts after the opening of the interrupting contacts is advantageously achieved according to the invention because as a result of the electrical transmission of the tripping impulse to the insulator 10 column 3 and the rapid mechanical transmission within the supporting insulator 3b the desired time-lead is given to the interrupting contacts.

As soon as pressure is present in the tube 2g the pneumatic mechanism 8q is operated to rotate shaft 8o and the spring operator 8b is reset through the linkage 8b, the shaft 8o and the cam 8m.

The closing operation is brought about by applying an impulse to the closing magnet 8f whereby the spring operator 8e unlatches and the valve 8d opens so that the gas line 9 is exhausted and the operating valve 2a is closed. The isolating contacts then close in the usual manner and the breaker is thus closed since the interrupting contacts had been opened only for a short period during the switching out process.

In the event of a fault arising in the conductor 10, for example, a severed wire, or if the tripping magnet 3l fails to operate, the interrupting contacts would not be able to operate after the order has been given so that the isolating contacts must undertake the function of interrupting the current, a task which they are not capable of performing, and they will consequently be damaged. In order to prevent this, the invention provides that for such cases use is made of the electrical conductor 10 or the pneumatic circuit which consists of the impulse valve 8h and the gas line 3r. As can easily be seen in FIG. 3, the gas lines 3r and 9 are simultaneously subjected to pressure at the time the breaker is tripped. Thus, the pressurized gas acts on the right-hand surface of the piston 3n so that the valve 3h will in this way be forced open consequently opening the interrupting contacts. The impulse valve 8h closes the pressurized gas source to the gas line 3r shortly after thus exhausting it. For this purpose the body of the valve 8i is constructed as a through-bored, self-holding differential piston so that 8i remains in the closed position as long as pressure is maintained on the gas line 9 side of the piston. 45 As soon, however, as this pressure is removed, for example, by closing the breaker, the body of the valve 8i is returned by means of the spring 8k as shown in the figure. A further failure could occur if the tripping magnet 8c failed to operate. The interrupting contacts of the column 3 would operate normally but the isolating contacts of column 2, after the order to switch out has been given, would not open so that the breaker, through its interrupting contacts, is switched out only for a short period and cannot be maintained in the open position. In order to prevent this, the invention provides the gas line 3q as a pneumatic transmitting means. When the interrupting contacts are opened the gas line 3q is subjected to pressure as soon as the valve 3h has opened. Thus, the pressurized gas, through the non-return valve 8l acts behind the driving piston of the switch-out valve 8a opening it thereby causing the isolating contacts to open in a similar manner to that described above.

The novel arrangement is not restricted to the examples 75 described above. In certain instances it can suffice that

the breaker pole consist of only one insulator column 3 while the insulator column 2, for example, contains only one isolator chamber. As a variation of FIG. 3, the tripping mechanisms 8c and 3l can also be connected in series.

I claim:

1. In a pressurized gas operated circuit breaker, the combination comprising an elongated tank containing a supply of pressurized gas, a first hollow insulator column upstanding on said gas supply tank and having its interior in communication with the interior of said gas supply tank, an interrupter chamber located at the upper end of said insulator column, pressure gas operated load interrupter contact means within said interrupter chamber, an operating valve at said interrupter chamber controlling admission of pressurized gas into said chamber from the interior of said insulator column to actuate said contact means, a valve rod extending upwardly through said insulator column from the base thereof for actuating said operating valve, electro-responsive control valve means, pneumatically actuated drive means connected to said valve rod at the base of said insulator column and which are controlled by said control valve means, a second hollow insulator column upstanding on said gas supply tank, an isolator chamber located at the upper end of and in communication with the interior of said second insulator column, pressure gas operated isolator contact means within said isolator chamber, conduit means connecting the interior of said isolator chamber with the interior of said gas supply tank, a pneumo-responsive control valve means located at the base of said second insulator column for controlling flow of pressurized gas from said gas supply tank to said isolator contact means for actuation thereof, circuit means connecting said load interrupter contact means and said isolator contact means in series between inlet and outlet terminals of said circuit breaker, a control block on said gas supply tank, electrical transmission means extending from said control block to said electro-responsive control valve means at said first insulator column, pneumatic transmission means extending from said control block to said pneumo-responsive control valve means at said second insulator column and auxiliary pneumatic transmission means extending from said pneumatic transmission means at said control block to and for actuating auxiliary pneumo-responsive means at said normally electro-responsive control valve means to actuate the latter in the event of a failure of the normally operative electro-responsive means.

2. In a pressurized gas operated circuit breaker, the combination comprising an elongated tank containing a supply of pressurized gas, a first hollow insulator column upstanding on said gas supply tank and having its interior in communication with the interior of said gas supply tank, an interrupter chamber located at the upper end of said insulator column, pressure gas operated load interrupter contact means within said interrupter chamber, an operating valve at said interrupter chamber controlling admission of pressurized gas into said chamber from the interior of said insulator column to actuate said contact means, a valve rod extending upwardly through said insulator column from the base thereof for actuating said operating valve, electro-responsive control valve means, pneumatically actuated drive means connected to said valve rod at the base of said insulator column and which are controlled by said control valve means, a second hollow insulator column upstanding on said gas supply tank, an isolator chamber located at the upper end of and in communication with the interior of said second insulator column, pressure gas operated isolator contact means within said isolator chamber, conduit means connecting the interior of said isolator chamber with the interior of said gas supply tank, a pneumo-responsive control valve means located at the base of said second insulator column for controlling flow of pressurized gas from said gas supply tank to said isolator contact means for actuation thereof, circuit means

connecting said load interrupter contact means and said isolator contact means in series between inlet and outlet terminals of said circuit breaker, a control block on said gas supply tank, electrical transmission means extending from said control block to said electro-responsive control valve means at said first insulator column, pneumatic transmission means extending from said control block to said pneumo-responsive control valve means at said second insulator column, and auxiliary pneumatic transmission means extending from said pneumatically actuated drive means for said valve rod at said first insulator column to actuate said control valve means at said second insulator column in the event of a failure of its normally operative pneumatic supply.

3. In a pressurized gas operated circuit breaker, the combination comprising an elongated tank containing a supply of pressurized gas, a first hollow insulator column upstanding on said gas supply tank and having its interior in communication with the interior of said gas supply tank, an interrupter chamber located at the upper end of said insulator column, pressure gas operated load interrupter contact means within said interrupter chamber, an operating valve at said interrupter chamber controlling admission of pressurized gas into said chamber from the interior of said insulator column to actuate said contact means, a valve rod extending upwardly through said insulator column from the base thereof for actuating said operating valve, electro-responsive control valve means, pneumatically actuated drive means connected to said valve rod at the base of said insulator column and which are controlled by said control valve means, a second hollow insulator column upstanding on said gas supply tank, an isolator chamber located at the upper end of and in communication with the interior of said second insulator column, pressure gas operated isolator contact means within said isolator chamber, conduit means connecting the interior of said isolator chamber with the interior of said gas supply tank, a pneumo-responsive control valve means located at the base of said second insulator column for controlling flow of pressurized gas from said gas supply tank to said isolator contact means for actuation thereof, circuit means connecting said load interrupter contact means and said isolator contact means in series between inlet and outlet terminals of said circuit breaker, a control block on said gas supply tank, electrical transmission means extending from said control block to said electro-responsive control valve means at said first insulator column, pneumatic transmission means extending from said control block to said pneumo-responsive control valve means at said second insulator column, a first auxiliary pneumatic transmission means extending from said pneumatic transmission means at said control block to and for actuating auxiliary pneumo-responsive means at said normally electro-responsive control valve means to actuate the latter in the event of a failure of the normally operative electro-responsive means, and a second auxiliary pneumatic transmission means extending from said pneumatically actuated drive means for said valve rod at said first insulator column to actuate said control valve means at said second insulator column in the event of a failure of its normally operative pneumatic supply.

4. In a pressurized gas operated circuit breaker, the combination comprising an elongated tank containing a supply of pressurized gas, a first hollow insulator column upstanding on said gas supply tank and having its interior in communication with the interior of said gas supply tank, an interrupter chamber located at the upper end of said insulator column, pressure gas operated load interrupter contact means within said interrupter chamber, an operating valve at said interrupter chamber controlling admission of pressurized gas into said chamber from the interior of said insulator column to actuate said contact means, a valve rod extending upwardly through said insulator column from the base thereof for actuating said operating valve, first control valve means having both electrically

and pneumatically responsive means for actuating said valve means, pneumatically actuated drive means connected to said valve rod at the base of said insulator column and which are controlled by said first control valve means, a second hollow insulator column upstanding on said gas supply tank, an isolator chamber located at the upper end of and in communication with the interior of said second insulator column, pressure gas operated isolator contact means within said isolator chamber, conduit means connecting the interior of said isolator chamber with the interior of said gas supply tank, a second control valve means having pneumo-responsive means for actuating the same, said second control valve means being located at the base of said second insulator column for controlling flow of pressurized gas from said gas supply tank to said isolator contact means for actuation thereof, a conduit including a control valve therein extending from said gas supply tank to said pneumo-responsive means for said second control valve means, said control valve being provided with both electrically and pneumatically responsive means for actuating the same, circuit means connecting said load interrupter contact means and said isolator contact means in series between inlet and outlet terminals of said circuit breaker, a control block on said gas supply tank, first electrical transmission means extending from said control block to said electrically responsive means on said first control valve means for actuating the latter to open position to actuate said drive means for said valve rod, second electrical transmission means to said electro-responsive control valve to actuate the latter to open position thereby to effect flow of pressurized gas through said

conduit from said gas supply tank to said pneumo-responsive means for said second control valve means, a first auxiliary pneumatic transmission line extending from said conduit on the discharge side of said control valve therein to said pneumatically responsive means for actuating said first control valve means in the event of a failure of the normally operative electrically responsive means to actuate said first control valve means, and a second auxiliary pneumatic transmission line for conveying pressurized gas from said pneumatically actuated drive means for said valve rod to said pneumatically responsive means for said control valve in said conduit thereby to actuate said control valve in the event of a failure of the normally operative electrically responsive means to actuate said control valve.
